UNITED STATES PATENT OFFICE.

HARRIE A. BALLARD, OF BOSTON, MASSACHUSETTS, ASSIGNOR TO UNITED SHOE MACHINERY CORPORATION, OF PATERSON, NEW JERSEY, A CORPORATION OF NEW JERSEY.

CHANNELING MACHINE.

Application filed November 3, 1920, Serial No. 421,485. Renewed October 12, 1925.

The present invention relates to channeling machines and is herein illustrated as embodied in a power-operated machine for channeling insoles for welt shoes. Many 5 features of the invention, however, are adapted for embodiment in channeling machines for operating upon other kinds of work, for example, soles for turn shoes.

In the development of power-operated 10 channeling machines, one of the most troublesome problems has been to provide efficient and reliable means for feeding and cutting the work which will operate satisfactorily at the desired high rate of speed, not 15 only while operating on the straighter portions of the work but also while the more sharply curved portions of the sole margin are being operated upon.

One object of the present invention is to 20 improve the construction and mode of operation of channeling machines to secure such relation between the feed of the work and the operation of the channeling knife or knives as best to facilitate accuracy of cutting, particularly at the ball and toe of the 25 sole, and to insure a maximum degree of efficiency in operation at all times.

With this object in view, an important 30 feature of the invention consists in the combination of cutting means, work-feeding means, and mechanism for operating them, so organized that the cutting means is moved opposite to the direction of feed of the work to cut the work while the work is being fed, 35 and then additional feeding of the work is effected while the cutting means is ineffective to cut the work. More specifically, and as embodied in the illustrated machine, this feature of the invention comprises a knife 40 reciprocating in the line of feed of the work and arranged to cut upon its backward stroke, and means for feeding the work against the knife while the knife is moving backwardly to cut the work and for feeding 45 the work with the knife during the forward or non-cutting stroke of the latter. By feeding the work against the knife while the knife is moving in the opposite direction, the length of cut produced will be equal 50 to the distance travelled by the knife plus the distance travelled by the work during the cutting operation. By imparting an additional feed movement to the work to advance it in unison with the knife while

the knife is being retracted idly into position to begin its next cutting stroke, the machine is enabled to make successive cuts the length of each of which is equal to the length of the knife stroke plus the length of the feed stroke. The above-described 55 mode of feeding and cutting the work permits the work to be fed and cut at the desired high rate of speed by means of intermittently effective feeding devices in which the length of the feed stroke is materially 60 less than in feed mechanisms of this type which have been heretofore employed in channeling machines. As the operator guides the sole to keep its curved edge continuously against the edge gage the sole 65 turns intermittently, the turning movements occurring as the work is released by the feeding means at the termination of successive feed strokes. By making the feed 70 strokes shorter, accuracy of cutting is facilitated inasmuch as the sole is then free to be turned at more frequent intervals.

In stating the above feature of the invention, only a single channeling knife was taken into consideration, although in the 80 illustrated machine a pair of knives are provided for cutting both an outer and an inner channel in a sole. Nevertheless in certain classes of work only one knife will be employed and the novel relation between the 85 feeding and cutting operations herein described and claimed may perhaps be more clearly visualized by considering first the feeding of the work with relation to the operation of a single channeling knife.

Considering therefore either one of the 90 channeling knives with which the illustrated machine is provided, the means shown in the drawings for advancing the work against that knife, while the knife is moving rearwardly to cut the work, comprises a reciprocating feed dog, and the means for advancing the work with the knife upon the forward or non-cutting stroke of the latter comprises a second reciprocating feed dog, 100 the feed strokes of which alternate with the feed strokes of the first feed dog. The feed dog which advances the work during the cutting stroke of the knife may be regarded as the main feeding means and the other feed dog, which imparts further feed movement to the work during the non-cutting stroke of the knife, may be regarded as an

auxiliary feeding means. For convenience of description, when the operation of a single knife only is being considered, the feed dog which functions while that knife is cutting will be referred to as the main feeding means and the other feed dog will be termed the auxiliary feeding means. Preferably, as shown, both the auxiliary feeding means and the knife are mounted upon a single horizontally reciprocating slide; the main feeding means is mounted upon a second horizontally reciprocating slide; and the two slides are mounted side by side and are actuated simultaneously in opposite directions and normally they are moved through strokes of substantially equal length. As a result the work normally is fed by the main feeding means through a distance substantially equal to that travelled in a backward direction by the knife, and inasmuch as the auxiliary feeding means functions after each effective operation of the main feeding means to impart an additional feed movement to the work substantially equal to the length of the knife stroke, the work is advanced in unison with the knife during the idle or return stroke of the latter. Consequently when the knife is again ready to cut, the relation of its cutting edge to the work will be the same as at the end of the preceding cutting stroke or, in other words, it will still be located at the forward extremity of the cut. Thus the knife can again cut throughout the entire length of its stroke while the work is being fed a like distance in the opposite direction by the main feeding means. By reason of the auxiliary feed movements above described, the present machine is enabled, at each successive cutting operation, to produce a cut which is approximately twice the length of the knife stroke and which is approximately twice as long as the distance travelled by the work while that cut is being made. The two feed dogs are serrated along their work-engaging faces so that the feed of the work is positive and inasmuch as the feed dogs operate in alternation, the feed of the work is substantially continuous.

It will be observed from the foregoing that the illustrated machine is provided with a reciprocating feed device effective upon its forward stroke to advance the work, a reciprocating knife effective upon its backward stroke to cut the work and means for operating said feed device and knife simultaneously in opposite directions. This organization constitutes another feature of the invention.

Heretofore, for successful operation, channelling machines have generally required the employment of relatively thick and high-grade material and they have not ordinarily been capable of use with insoles of such inexpensive, soft or thin material as economy

often demands in the manufacture of insoles.

Another object of the present invention is to provide a channelling machine which is adapted to operate satisfactorily upon insoles which are made of thin and relatively soft, weak stock.

To the accomplishment of this object, the invention contemplates the construction and arrangement of its parts in such a manner as to insure the making of a cleaner cut in the work and to avoid tearing of the stock. More specifically, this feature of the invention consists in certain improvements in the construction and organization of the knife-actuating mechanism whereby a pair of knives are made to operate in alternation on the work to cut outer and inner channels such as are required in insoles for welt shoes. By causing the knives to cut alternately instead of in unison, the cutting strain is divided and distributed evenly over the entire period of operation upon the work so that the thrust against the work is never more than substantially half as great as that caused by similar knives operating simultaneously. Hence, there is less tendency to tear or weaken the stock and cleaner cuts will be produced.

When two channelling knives are employed, as in the illustrated embodiment of the invention, one knife is mounted upon each of the two horizontally reciprocating slides hereinbefore mentioned. The two knives are thus mounted independently of each other and normally they are movable simultaneously through equal strokes in opposite directions. Each feed dog is movable in opposition to the direction of movement of one of the knives and in unison with the other knife, and each feed dog may be regarded as the main feeding means with respect to the knife which moves in opposition thereto, and as an auxiliary feeding means with respect to the operation of the knife which moves in unison therewith.

There is also associated with each knife a presser member or gage which yields vertically and reciprocates horizontally in unison with the knife. The presser gage rests upon the work, preferably in close proximity to the cutting edge of the knife, to regulate the depth to which the knife penetrates the work and to hold the work down upon its support.

At the toe or other more or less sharply convex portion of the margin of a sole, the portion to be acted upon by the outer channel knife extends along a curve of a greater radius than the corresponding portion of the sole margin which is to be acted upon by the inner channel knife or, in other words, that portion of the outer channel which is to be cut around the toe is longer than the corresponding portion of the inner channel.

- Accordingly, to avoid undesirable overlapping of successive strokes of the inner channel knife at the toe and the resulting danger of mutilation of the sole material, it is 65
 5 desirable that the stroke of the inner channel knife slide should be variable so that the inner channel knife may have a relatively long stroke, substantially equal to the stroke of the outer knife, while operating 70
 10 along the slightly curved lateral margin of the sole, and a stroke somewhat shorter than that of the outer knife while operating around the more sharply curved toe portion of the sole. When the length of stroke of 75
 15 the inner knife slide is shortened, the length of stroke of the feed dog carried by the inner knife slide is also correspondingly shortened. Consequently the sole will then advance less rapidly and may be more easily 80
 20 manipulated to avoid being injured by the knives.

For supporting the work, I employ, preferably, a flat rotary table in conjunction with which I employ an edge gage and a chamfering knife. These are combined and associated, in a novel manner, so that all are 85
 25 adjustable simultaneously transversely of the line of feed, relatively to the channeling knives, so that the edge of the innersole is 90
 30 uniformly chamfered, and yet the distance between the bottoms of the channels and the adjacent edge of the innersole may be varied as desired. While the chamfering knife, the work table and the edge gage are 95
 35 bodily adjustable coincidently, the chamfering knife also has an independent movement or stroke which is desirable for causing it to make a clean cut.

In the foregoing, I have referred to only 40 what may be regarded, perhaps, as the more prominent features of the machine, but it will be understood from the following more detailed description that the invention 105
 45 comprises various other features of construction and relative arrangement of parts which are of decided advantage and importance.

On the drawings,—

Figure 1 is a view in front or end elevation of a channeling machine embodying the invention.

Figure 2 is a similar view of the major portion of the machine, but on a larger scale.

Figure 3 is a side elevational view of the portion of the machine shown in Fig. 2.

Figure 4 is a sectional view, on a fairly large scale, taken along the line 4—4 of Figure 3.

Figure 5 is a vertical section on the front-to-rear section of the machine.

Figure 6 is a section on the line 6—6 of Figure 5.

Figure 7 is a section on the line 7—7 of Figure 5.

Figure 8 is a horizontal section on the line

8—8 of Figure 3, taken through the main 65 shaft.

Figure 9 shows a side elevation (opposite from that in Figure 3) and illustrates the means for moving the knives and feed dogs from the work.

Figure 10 is an enlarged section through a portion of an innersole undergoing channeling.

Figure 11 is a similar section through a portion of a completed innersole.

Figure 12 is a section on the line 12—12 of Figure 7, looking in the direction of the arrow.

Figure 13 is an elevational view of the feed dog and the associated knives and presser gages and illustrates one of the feed dogs as being provided with a toe to extend between the presser gages and the knives.

Figure 14 is a section on the line 14—14 of Figure 13; and

Figure 15 is an end view of the elements shown in Figure 13.

Persons skilled in the art, reading the following description of the machine illustrated in the drawings thus briefly referred to, will understand that, although I have selected for illustration the best form or embodiment of the invention now known to me, nevertheless the invention is capable of various other embodiments, that various details of construction which I hereinafter describe may be changed without departure from the scope of the invention, and that the phraseology herein employed is for the purpose of description rather than that of limitation.

Proceeding to a description in detail of the said channeling machine, it is, of course, mounted upon a suitable standard or base, a portion of which is illustrated in Figure 1 and indicated at 20. This standard is illustrated as being provided with a head 21 to which the operative portion of the machine may be bolted or otherwise secured. 22 indicates a goose-neck frame, the base 23 of which is affixed to the head 21. This frame is provided with a lower horizontal portion 24 having guideways 25 on which a slide 26 is mounted.

This slide or carrier supports a rotatable work table or support, and is adjustable transversely of the line of feed of the work so as to vary the distance between the channels and the edge of the work or innersole. This slide 26 straddles the guideways 25 and is provided with gibs 27 which take thereunder as shown in Figure 1. The rotatable work table is indicated as a whole at 28 and is best shown in Figure 5. It is circular in plan view, and affords a flat supporting face for the work. Near its perimeter, this table is provided with radial

grooves, corrugations or teeth 29 for the purpose of engaging the work. The table is freely rotatable about a vertical axis, and

120

125

to this end it is provided with a depending stem 30 which is journaled in a bearing 31 formed in the bottom portion of the slide. Just above the stem, the table is provided with a radial flange 32, and a suitable form of anti-friction bearing is introduced between the flange 32 and the bottom of the slide 26. As shown, this bearing may comprise two hardened steel rings or washers 33, 34, and a series of balls or spheres 35 held in a cage 36. This bearing supports the end thrust of the table, and, in conjunction with the bearing 31 and the stem 30, holds the table against lateral vibration.

15 The work-supporting portion of the table is undercut or beveled so as to be more or less frusto-conical, as indicated in Figure 5. The slide 26 has an upstanding semi-cylindrical wall 37 which partially encloses the work table and which conceals it when the machine is seen in front or end elevation, the top of this wall 37 being only slightly lower than the work-supporting surface of the table. Any suitable mechanism, under 20 the control of the operator, may be utilized to adjust the table and its supporting slide or carrier, such, for example, as the mechanism illustrated upon the drawing and which comprises a lever 38 pivoted upon a bolt 39 and provided with a cam arm 40 (see Figures 5 and 7). The pivot bolt 39 is secured to a segmental plate 51 (hereinafter described) and is held in place by a nut 42. The cam arm 40 is formed with a 25 cam slot 43, as shown in dotted lines in Figure 7, into which extends a pin 44 provided with a roll 45. The upper end of the pin projects through a slot 46 in the slide 26 and is adjustably secured thereto by a nut 47 and a washer 48, the upper extremity of the pin being appropriately threaded to receive the nut. The sides of the pin 44 may be slabbed off so as to fit between the walls of the slot 46 and be thus held against 30 rotation relatively thereto, such flattened or slabbed sides being indicated at 50. The cam arm 40 is approximately at right angles to the lever 38 and the latter projects from the side of the frame so that it may be manipulated by the operator. A segmental plate 51 is secured upon the base of the frame by any suitable fastenings, and it and the lever 38 are provided with interlocking means by which the lever may be held in 35 locked position at several points in its swinging movement. For example, the lever may have a handle 52 pivoted thereto by the pivot 53 and provided with a latch 54 for engaging the members on the segmental plate. The handle may be provided with the lug 55, between which and the lever 38 may be interposed a spring 56 (see Figure 1). To the peripheral surface of the segmental plate I attach locking members indicated at 57, 58 and 59. The member 58

may be formed integrally with the segmental plate or it may be secured thereto in any suitable manner. The members 57 and 59 are preferably adjustable and are held in place by screws 60, 61, passed through the slotted end portions of said members into the body of the plate. Each of these three members is provided with a notch 62 with which the latch of the handle may be engaged. Obviously, by lifting the handle so as to disengage the latch from one of the notches, the lever may be moved in one direction or the other to adjust the slide and the work support or table thereon back and forth as may be desired. While 80 the mechanism herein described for supporting the work possesses certain features of novelty and desirability, nevertheless, so far as other features of the machine are concerned, it may be supplanted by any other 85 suitable mechanism for supporting and adjusting the work.

In the drawings I have shown a channeling knife for cutting obliquely into the substance of a sole toward the sole edge to 90 form a channel and an inner lip, and an edge-slitting knife for cutting inwardly from the edge of the sole to form a feather and an outer lip. For certain classes of work, however, a single knife only may be 95 used as previously stated. The knives are independently supported and are operated simultaneously in opposite directions. The knives receive their movement primarily from a shaft driven from a suitable source 100 of power. The upper portion of the goose-neck frame, as shown in Figures 3 and 8, is provided with bearings 63, 64, having bushings 65, 66, in which the main shaft 67 is journaled. It is from this shaft that 105 the various power-operated parts of the machine are driven. The shaft itself may be provided with a loose pulley 68, formed as one member of a friction clutch to engage a clutch member 69 pinned to the end of 110 the shaft. The pulley itself may be driven by a belt 70 from a separate motor from a counter-shaft or other source of power supply. Any suitable means may be utilized to frictionally engage the pulley 68 with the 115 complementary clutch member 69, such, for example, as a bifurcated wedge 71 located between the frame and a complementary formed collar 72 loosely mounted on the shaft 67. Between this collar and the hub 120 of the pulley, I may place a plurality of balls 73 held in a cage 74. The bifurcated wedge is illustrated as secured to the end of a rod 75 connected to a treadle (not shown) so that it may be raised and lowered by the operator. In this way, I provide for driving the main shaft 67 at any desired rate of speed up to the speed of the pulley 68. In channeling the end of an innersole, the clutch-operating wedge may be lowered so 125 130

as to permit the clutch member 69 to slip relatively to the pulley so as to reduce the speed of rotation of the main shaft and the speed at which the knives are operated.

5 The two knives may be termed, in order to distinguish them, the outer and the inner grooving or channeling knives, inasmuch as one cuts from the outer edge of the inner-sole and the other cuts into the body of the 10 innersole at a point more remote from the edge thereof. These two knives are indicated at 76 and 77 respectively, and they are secured, by means to be described, to knife carriers 78 and 79. Each knife carrier is 15 reciprocated horizontally or in a plane parallel with the upper surface of the table or work support, and in addition is capable of movement towards and from the face of the work table. The knife carrier 79 for the 20 inner knife 77 comprises a bar, which is rectangular in cross section as shown in Figure 7, and which is provided with a head 80 at its lower end to which the knife is secured. Said knife carrier is mounted in a 25 slide or carriage 81 which is adapted to reciprocate horizontally in a guideway afforded by the main frame. To this end, the main frame, which is hollow, is provided in its side walls with rectangular apertures 82, 30 into which the slide extends and which afford a guideway therefor, and the slide is provided with extended end portions 83, 83 (see Figure 4), which fit within the sockets or recesses 82. The knife carrier 79 extends 35 into a rectangular socket 84 in the slide, and its upper portion is in the form of a sleeve, being hollow as shown, so as to afford a recess 85 to receive a compression spring 86. The lower end of the spring 40 is seated in the socket and its upper end bears against a screw 87, which is screwed downwardly into the slide 81. The function of the spring is to force the knife carrier downwardly towards the work table, 45 and to hold the knife 77 yieldingly in its cutting position. It is necessary, of course, that the downward movement of the knife carrier should be limited, and for this purpose a rod 88 is passed downwardly through 50 a central aperture in the nut, and its lower threaded end is screwed into a threaded socket 89 at the lower end of the recess 85. The upper end of the rod 88 is threaded to receive a nut 90 which normally rests upon 55 the upper end of the nut 87, and thus limits the extent to which the knife carrier may be forced downwardly by the spring. The nut 87 is, of course, adjustable axially in the slide and the nut 90 is adjustable on the rod 60 88 so that the extent of downward movement of the knife carrier may be varied. The upper threaded end of the rod passes loosely through the nut 87. The inner knife 77, which is attached to the knife carrier 65 79, is formed with a cutting edge 91 to cut a channel *a* in the work, as shown in Figure 10, so as to form a flap or rib *b*. Said knife is further formed with a second cutting edge 92 which slits the flap or rib so as to remove the outer portion thereof, which is indicated 70 at *c* in Figure 10, thereby leaving the flap *b* relatively narrow in width. These cutting edges 91 and 92 are formed on a shank 93 which is arranged at an acute angle to the knife carrier, as shown in Figure 5. For 75 this purpose, the knife carrier 79 has a lateral extension 94, to which a block 95 is secured by a bolt 96 and nut 97 (see Figure 6). The block and lateral extension of the knife carrier are formed with an interlocking projection 98 and recess 99. The block 95 is provided with a groove or guideway 100 to receive the shank 93 of the cutter. 80

A cap plate 101 is clamped against the knife shank and the block 95 by the bolt 96 and 85 the nut 97, these last-named members 96, 97 rigidly securing the several parts together. The knife may be adjusted lengthwise by an abutment screw 102 passed through a rib 103 on the lateral extension 94 of the knife 90 carrier, and abutting against the end of the knife shank. A lock nut 104 serves to prevent accidental rotation of the abutment screw. The outer channeling knife, which is indicated as a whole at 76, is mounted upon the knife carrier 78 previously referred to. This knife carrier has a relatively large laterally-extending head 105. To this head is secured a block 106 (see Figures 7 and 100 12) which holds the knife 76. The knife itself is shown in Figures 5 and 10 as being provided with a cutting edge 107 for forming the lip *d* in cutting the channel *e*. It is also provided with a supplemental cutting edge 108 which slits the lip and severs the 105 strip, indicated in Figure 10, at *f*. The shank of the knife 76 is secured to the removable block 106 by screws indicated at 109, 110, and is arranged in a groove or recess in the block, into which an adjustable 110 abutment screw 111 extends, as shown in Figure 5. A lock nut 112 holds the abutment screw against dislocation after being adjusted. The block 106 is secured to the extended head 105 of the knife carrier 78 by 115 a screw 113. The knife carrier 78, except as herein described, is substantially identical with the knife carrier 79, and it is mounted identically therewith in a slide or carriage 114 substantially similar to the slide 120 or carriage 81 and arranged to reciprocate in a rectangular guideway 82 in the main frame. In Figure 3, which shows the slides in end view, they can be seen as arranged in parallelism face to face and located to 125 slide in one of the guideways 82. Inasmuch as the knife carrier 78 and the horizontally moving slide on which it is mounted are substantially similar to the knife carrier 79 and the slide or carriage 81, they need not 130

be described, it being understood that the knife carrier is pressed downwardly by spring mechanism like that described in connection with the knife carrier 79.

5 Each knife carrier is provided with a presser member or gage which rests upon the surface of the work in proximity to the associated knife so as to hold the work down as the knife is cutting, and to limit the 10 depth of the cut made by the knife. In Figure 14, these two presser members are indicated at 115 and 116 respectively, the former being associated with the inner channeling knife 77 and the other being associated with the outer channeling knife 76. These two presser members are likewise shown in face view in Figure 5. As these two presser members are secured to their respective knife carriers by substantially the 15 same means, I will refer to only one of them in describing it. It consists of a relatively flat metallic bar, having a rounded lower edge to meet the oncoming work, as indicated at 117. It is placed flat against the 20 head of the knife carrier 79, for example, as shown in Figure 4, and is provided with a rib 118 to fit a groove 119 formed in the face of the knife carrier (see Figure 5). The presser member is adjustably secured 25 to the knife carrier by a screw 120 passed through the head of the latter, and the presser member may be adjusted by an adjusting screw 121 threaded into the head in parallelism with the screw 120 and having a conical tip 122 to engage the upper end of said 30 presser member. Any other suitable means, however, may be utilized for effecting a minute adjustment of the presser member relatively to its associated knife carrier and 35 the knife carried thereby. As illustrated, the adjusting screw 121 is provided with a lock nut 123. Inasmuch as each presser member is attached to and supported by its associated knife carrier, it is adapted to 40 yield relatively to the work or towards and from the plane thereof. The two knife carriers, as shown in Figure 5, are placed side by side, viewing them in the direction of the movement of the work.

45 As previously stated, the knife carriers are reciprocated horizontally or in planes parallel with the plane of the surface of the work table but in opposite directions, this being accomplished by reciprocating the slides in which said knife carriers are mounted simultaneously in opposite directions in guides afforded by the main frame of the machine. To accomplish this result, mechanism must be employed for reciprocating said slides. The slide 81, as 50 shown in Figure 4, is provided with a dependent lug 124 which is connected by a stud 125 and link 126 with a two-armed lever having the arms 127 and 128. This lever, 55 as best shown in Figures 8 and 9, is provided with a duplex hub 129 mounted loosely upon a shaft 130 journaled in bearings 131, 132, extending from the side of the main frame. The upwardly extending arm 128 is pivoted to an eccentric rod 133 provided with an eccentric strap 134 placed upon an eccentric 60 135 secured to the main drive shaft 67, as shown in Figure 8. Any suitable form of pivotal connection, such as a stud 136, may be utilized to connect the arm 128 to the eccentric rod 133. The depending arm 127 of the two-armed lever is provided with an elongated slot 137, in which may slide a rectangular block 138 (see Figure 4), in which 65 is journaled a stud 139 extending inwardly from the link 126. Preferably the end of the link is bifurcated (as shown in Figures 2 and 4) so as to straddle the arm 127, and the pivot 139 is threaded at its ends to receive nuts one of which is indicated at 140. By 70 reason of the construction thus noted, the rotation of the main shaft 67, through the eccentric, the double-arm lever and the link, causes the reciprocation of the slide 81 and the knife carrier 79.

75 The extent of reciprocation of the knife carrier, however, may be varied by moving the pivot 139 in the slot 137 towards and from the axis of oscillation of the two-arm lever 127, 128. As shown in Figure 2, the pivot 139 and its block 138 occupy the lowermost position in the slot 137. By means of a rock lever 141, which has a lug or stud 142 projecting under a rib 143 formed on the link 126 (as shown in Figure 2), the link may be 80 moved upwardly about the stud 125 so that the stud 139 will be moved towards the axis of oscillation of the two-armed lever 127 and 128, and thus decrease the extent of reciprocation of the slide 81 and the knife carrier 85 therein mounted, all for a purpose which will be subsequently explained. The rock lever 141 is under the control of the operator and may be raised and lowered as desired by any suitable means. For example, the 90 said rock lever is illustrated as being secured to a rock shaft 144 journaled in bearings 145, 146 (see Figure 8), and having at its rear end an arm 149 which may be connected by a chain, rod or other suitable connection 150 (see Figure 1) with a treadle, not shown. The depression of the treadle rocks the shaft 144 and raises the free end of the rock lever 141. The downward movement of the rock lever may be limited by a 95 finger 152 formed thereon and adapted to engage the main frame, as shown in Figure 2. The pivot pin 139 is yieldingly maintained in the lower end of the slot 137 of the arm 127 by a spring 153, one end of which is 100 attached to a lug 154 on the link 126 and the other end of which is secured to a pin 155 105 projecting from the face of the slide 81; and consequently, when the operator raises the treadle, the free end of the link 126 is moved 110

115 120 125 130 135 140 145 150 155 160

downwardly to increase the extent of reciprocation of the knife carrier slide 81 and thus to lengthen the stroke of the inner channeling knife 77.

5 The slide 114 is provided with a laterally and downwardly extending head 156 which serves a double function; that is, it serves as a member of the transmitting connections by which the slide is operated and it 10 also serves as a support for an edge gage subsequently to be described. To this head or extension 156 a link 157 is pivoted by a pivot 158, and the link in turn is connected by a pivot 159 with a rock lever which 15 is mounted loosely on the shaft 130 and is provided with two arms 160, 161. The upper end of the arm 161 is connected by a pivot 162 to an eccentric rod 163 formed with a hub or strap 164 encircling an eccentric 20 165 formed on the same hub on which the eccentric 135 is formed, as shown in Figure 8. This hub is secured to the shaft 67 by a pin 166. The two eccentrics 165 and 135 are disposed diametrically opposite each 25 other, and hence, through the connections described, the two slides 81 and 114, and the parts carried thereby, are reciprocated simultaneously in opposite directions horizontally. Further, the eccentrics preferably 30 are of the same diameter, as shown, and the connections between the eccentrics and the slides 81 and 114 are so constructed and arranged that when the pivot 139 occupies its lowest or normal position with respect to the 35 slotted arm 127, as shown in Fig. 2, the slides 81 and 114 will be reciprocated through strokes of equal length. Consequently, under normal operating conditions the feed strokes imparted to the work will 40 be of the same length as the knife strokes, thus providing for maximum efficiency in the feeding and cutting of the work as will hereinafter appear. As a matter of construction, the head 156 of the slide 114 may be bifurcated, as shown in Figure 7, so as to straddle the end of the link 157; and similarly the lower end of the arm 160 may be bifurcated to straddle the other end of said link. The arm 160, shown in side elevation 50 as in Figure 9, is inclined at an angle so as to extend forwardly for the purpose of bringing its end into alignment with the head 156.

The member 156, which is formed on the 55 slide 114, serves both as a support for an edge gage and for a chamfering knife, each of which is adjustable towards and from the path of movement of the work when it is being fed. The under side of the head is provided with an undercut or dove-tail guideway 167 (see Figures 5 and 12) in which is mounted a slide carriage or support 168. This carriage consists of a bar formed to fit within the guideway 167 and the carriage is movable bodily with the main car-

riage 26 which supports the rotary table or work support. For this purpose, the slide or carrier 26 is provided with an upstanding pin 169, the end of which is flattened to extend into a transverse groove 170 formed in 70 the under side of the slide 168. Hence, when the slide 26 is adjusted, the carrier or slide 168 moves simultaneously with it. At its forward end, the slide 168 is provided with an upstanding member 171 (see Figure 75 3) against which the edge of the work may be pressed and which thus serves as an edge gage. This member may be formed integrally with the slide 168 or adjustably secured thereto as may be desired. The slide 168, however, at its forward end is provided with a downwardly extending head 172 (see Figure 5) which is recessed to receive the shank of a chamfering knife 173, secured in place by a screw 174 passed through a slot 80 in the knife shank. The head 172 is inclined so that it fits under the frusto-conical portion of the work table, and the knife edge projects upwardly in close proximity to the circular edge of the table so as to chamfer that portion of the innersole which extends beyond the perimeter of the table into engagement with the edge gage 171, as illustrated in Figure 3. As the carrier for the work table is adjusted horizontally in reference to the channeling knives, and in a direction transverse to the lines of reciprocation of said knives, the edge gage and the chamfering knife are adjusted bodily therewith. The chamfering knife, however, must be moved or reciprocated longitudinally of the path of movement of the work, and, for this reason, its supporting carrier or slide 168 is supported by the head 156 of the transversely movable slide 114 so as to reciprocate therewith, the pin and slot connection 169 and 170 between the main carriage or slide 26 and the chamfering knife slide 168 permitting this movement without affecting the simultaneous adjustment of the chamfering knife with the work table. This connection between the main carriage 26 and the slide 168 causes the edge gage to move with the channeling knives so as to maintain a constant relation thereto while providing a bearing point for the turning of the sole as the latter is guided by the operator.

As previously stated, as each channeling knife moves rearwardly, that is in a direction opposite to the direction of feed of the work, it cuts the material of the innersole, the innersole at this time being fed forwardly or in the opposite direction. For accomplishing this result, I employ two feed dogs, one associated with each of the knives and movable horizontally therewith. In addition to this horizontal movement, however, each feed dog is reciprocated vertically so that it has a four-way motion. These two feed dogs are indicated at 180 and 181 re-

spectively. The feed dog 180 is associated with the slide 81 in which the knife carrier 79 is mounted, and the other feed dog 181 is associated with the knife carrier 78 and is mounted in the slide 114. These two feed dogs are arranged side by side (as shown in Figures 3, 13 and 15), and are serrated on their under faces so as to provide teeth for engaging the surface of the work. As shown, the serrated faces of the feed dogs are of substantial area to enable them to prevent the sole from buckling at the portions about to be presented to the knives. The feed dogs are mounted on the lower ends of carriers 182, 183, respectively. The carriers are provided with downwardly extending lugs 184 to which the feed dogs are secured by screws 1840.

The feed dog carriers 182, 183, are substantially identical in construction so that I shall describe only one of them. Each comprises two sections 1840, 186, which are placed end to end (as shown in Figure 4), and which are recessed to receive between them a spring 187 which tends to hold them apart. The upper section 186 is formed with a transverse guideway 1870 to receive a block 188 encircling an eccentric on the main shaft 67. There are two eccentrics, one for each feed dog carrier, as indicated at 189, 190, and they are arranged in diametrically opposite relations, so that, as one feed dog is being depressed, the other is being raised, and vice versa. A rod 191 is passed through the lower section 185 of the feed dog carrier, and its upper end is screwed into a threaded bore formed in the upper section 186. The lower end of the rod is provided with a head 192 which limits the downward movement of the spring-pressed section 182. By this construction, I provide for a yielding engagement of each feed dog with the surface of the work, and yet permit the feed dog to receive a four-way motion, as previously stated. The arrangement is such that after each feed dog has been depressed into engagement with the work the respective spring 187 is somewhat compressed so that the serrations in the bottom face of the feed dog are forced into the material of the sole thus insuring that the sole will be firmly gripped and positively fed by the feed dog. The rod 191 is held against accidental rotation by a screw pin 193 passed through the lug 184 of the feed dog carrier and having its end entering one of a series of grooves formed in the head 192 of said rod.

It will be seen from the foregoing, that, as the main shaft is rotated, the two slides 81 and 114 are reciprocated in opposite directions; and that, as each slide moves forwardly or in the direction of the feed of the work, the associated feed dog, which is then depressed into its engagement with the work,

feeds the work forwardly, the other feed dog in the meantime being raised and moving in the opposite direction. The parts are so adjusted that, during each complete rotation of the main shaft, each feed dog will be depressed into engagement with the work, then moved forwardly to advance the work, then lifted, and then caused to move rearwardly in the opposite direction while out of engagement with the work. As each feed dog moves the work forwardly, the associated channeling knife and the associated presser member or gage moves with the work, without the knife at this time cutting the work. During this forward movement of these parts which I have enumerated, the other feed dog is out of engagement with the work. If desired, the end of each feed dog may abut the face of the associated presser member. It is not essential that the two presser members 115 and 116 should be so closely adjacent as to be contiguous, as illustrated in Figure 5 for example, as they may be separated at their lower ends, as shown in Figure 14, in which case the feed dog 181 may be provided with a longitudinal toe or extension 194 to extend between them and to a point beyond the two channeling knives so as to ensure that the work will be fed beyond the knives when the cut is completed.

The feed dogs are moved forward in effective feeding engagement with the work throughout the length of the forward movements of the slides 81 and 114. Inasmuch as these slides also carry the knives, the strokes of the feed dogs, and consequently the feed movements of the work, are equal in length to the strokes of the knives. It will be seen therefore that each feed dog, while functioning as the main feeding means with respect to the knife travelling backwardly in opposition thereto, will advance the work a distance equal to the length of the backward cutting stroke of said knife, and further that each feed dog, while functioning as the auxiliary feeding means with respect to the knife travelling forwardly and idly in unison with said feed dog, will feed the work forwardly in unison with said knife and through a distance equal to the length of knife stroke. Consequently each time a knife is retracted, the work is fed along with the knife so that when the knife again moves backwardly there will be no lost motion between the knife edge and the work but the knife will begin to cut immediately. It is of importance that the relation between the knife strokes and feed strokes be at least approximately as above described if the knives are to cut practically without idle movements at the start of their strokes or, in other words, if a maximum degree of efficiency is to be attained in the operation of the machine.

By reason of the large area of the serrated work-engaging faces of the feed dogs 180 and 181 and the fact that the serrations are embedded firmly in the material of the 5 sole by the compression of the springs 187, it follows that the sole is firmly gripped and positively fed, and further that the sole is not free while thus gripped to be turned in response to guiding pressure of the operator 10 tending to maintain the edge of the sole against the edge gage. The sole, however, is free to be turned as each feed stroke terminates or during the interval when the compression of the spring 187 associated with 15 one feed dog is being relieved and before the spring associated with the other feed dog has been materially compressed. In the present machine, by reason of the fact that the sole and the knife are moved in opposite 20 directions while the cut is being made, the length of stroke of the feed dogs may be, and preferably is, made less than the length of stroke of the feed devices in many machines heretofore used. The feed strokes 25 being made shorter it will be seen that the periods when the sole is free to be turned by the operator occur more frequently. This makes for greater accuracy in cutting since the operator is thus enabled to impart a 30 greater number of turning movements to the sole per given length of sole edge. Consequently it is easier to maintain the sole against the edge gage so as to prevent the work from deviating from its proper relation 35 to the knives, and thus to insure against liability of the sole to "throw out" at the toe or at the ball with resulting mutilation of the material of the sole. Furthermore, the relative position of the knives and the work 40 may be more easily changed to compensate for any such deviation of the work from its proper course relatively to the knives as may have occurred.

I provide means by which the channeling 45 or grooving knives may be bodily elevated from the surface of the work. Such means may comprise a lever pivoted at 200 (as shown in Figure 9), and having one arm 201 which may be connected by any suitable connection with a treadle, not shown, and having another arm 202 which enters the framework through an aperture formed therein and is arranged under two plates 203, 203, clamped to the rods 88 of the knife carriers 50 by the nuts 90 and nuts 204 screwed upon the rods 88. By depressing the free end of the lever, the two knife carriers and the presser members 115, 116, secured thereto or associated therewith, may be lifted vertically away from the face of the work or 55 away from the work table.

In operation, the shank of an innersole is introduced between the work table and the two feed dogs, the latter yielding to permit 60 this insertion, and the edge of the innersole

is brought to bear against the edge gage 177. The machine is then set in operation, and, as the work is fed by the feed dogs, the channeling knives 76 and 77 cut the channels in the work and form the lips *b d* (Figure 70 10). After completing its forward cut, each knife moves forward with the work, during which time the other knife makes its cut. As the work is fed, the chamfering knife 75 chamfers the innersole, as shown in Figure 10. The operator at will adjusts the main slide which supports the work table, and thus varies the distance at which the channels are formed from the edge of the innersole. When the toe of the innersole is reached, 80 the operator may, by moving the clutch-controlling yoke 71, decrease the speed of the main shaft 67, and at the same time may reduce the length of the reciprocations of the inner channeling knife by raising the 85 free end of the link 126 until its approaches the axis of oscillation of the two-armed lever 127, 128, by which the knife-carrying slide is operated.

As it is sometimes desirable to prevent a 90 cessation of reciprocation of the inner knife-carrying slide 81, I provide an abutment screw 205 arranged in a path of the block 138 on the pivot 139, as illustrated in Figures 2 and 4, so that the axis of the pivot 95 139 may not be brought into alignment with the axis of the shaft 130 on which the two-armed lever 127, 128 is fulcrumed.

After the innersole has been channeled, 100 the two lips *b* and *d* may be compressed together and condensed and compacted, as illustrated in Figure 11, with the lip *d* bent inwardly toward the middle portion of the innersole and lying upon the lip *b*, as shown in Figure 11. After this, the face of the 105 innersole may be covered with an adherent layer of canvas or the like, but this forms no part of the present invention and is not claimed herein.

Having thus explained the nature of my 110 said invention and described a way of making and using the same, although without attempting to set forth all of the forms in which it may be made or all of the modes of its use, what I claim is:

1. A channeling machine comprising independent channeling knives, means for simultaneously reciprocating said knives in opposite directions, and means associated and movable in unison with each knife for feeding the work while the other knife is cutting in an opposite direction. 120

2. A channeling machine comprising feed dogs, means for simultaneously operating said dogs in opposite directions to impart a substantially continuous feed to the work, a pair of channeling knives, and means for reciprocating said knives in opposite directions to cut in alternation. 125

3. A channeling machine comprising chan-

- neling knives, means for operating said knives to cause them to cut in alternation, means for feeding the work in a direction opposite the cutting strokes of said knives, 5 and a presser gage associated with each knife.
4. A channeling machine comprising channeling knives, means for operating said knives to cause them to cut in alternation, 10 means for feeding the work in a direction opposite the cutting strokes of said knives, a presser gage associated with each knife, and means by which each presser gage is caused to reciprocate with its associated 15 knife.
5. A channeling machine comprising channeling knives, means for operating said knives to cause them to cut in alternation, means for feeding the work in a direction opposite 20 the cutting strokes of said knives, a presser gage associated with each knife and arranged to bear on the work adjacent the cutting edge of said knife, and means for causing each gage to reciprocate with its associated knife.
6. A channeling machine comprising channeling knives, means for operating said knives to cause them to cut in alternation, a feeding device associated with each knife and 25 movable therewith, and means by which each said device is caused to feed the work in a direction opposite the cutting stroke of the non-associated knife.
7. A channeling machine comprising channeling knives, a presser gage and a feed dog associated with each knife, and mechanism for reciprocating said knives and their associated presser gages and feed dogs simultaneously in opposite directions.
- 40 8. A channeling machine comprising channeling knives, mechanism for feeding the work, and mechanism for reciprocating said knives simultaneously in opposite directions, a presser gage having a fixed relation to each knife and movable therewith, and a feed dog movable with each knife and capable of independent movement toward and from the work.
9. A channeling machine comprising channeling knives, means for causing said knives to cut in alternation, and a feeding device associated with each knife for feeding the work to the other knife during the cutting stroke thereof.
- 55 10. A channeling machine comprising channeling knives, means for reciprocating said knives simultaneously in opposite directions to cut in alternation, and means associated with each knife and movable in a straight path for feeding the work against the cutting stroke of the other knife.
11. A channeling machine comprising channeling knives, means for reciprocating said knives simultaneously in opposite directions to cut in alternation, means associated and
- movable with each knife for feeding the work against the cutting stroke of the other knife, and an edge gage movable transversely of the direction of movement of said knives. 70
12. A channeling machine comprising parallel slides, and mechanism for simultaneously moving said slides in opposite directions, each slide being provided with a channeling knife and a work feeding device. 75
13. A channeling machine comprising parallel slides, and mechanism for simultaneously moving said slides in opposite directions, each slide being provided with a channeling knife, a presser gage and a work-feeding device. 80
14. In a channeling machine, a slide, means for reciprocating said slide, a knife and a feed dog supported by said slide and movable therewith, and means for independently reciprocating said feed dog in lines transverse to its lines of movement with said slide, whereby a four-way motion is imparted to said feed dog. 85
15. A channeling machine comprising a pair of parallel slides, a channeling knife and a feed dog attached to and movable with each slide, and means for simultaneously reciprocating said feed dogs in opposite directions but in lines transverse to the paths of movement of said slides. 90
16. A channeling machine comprising a slide, means for reciprocating said slide, a channeling knife, a knife carrier mounted in said slide and movable therewith, a feed dog, 100 a feed dog carrier mounted in said slide and movable therewith, and means for reciprocating the last-mentioned carrier perpendicularly to the path of movement of said slide.
17. A channeling machine comprising a channeling knife, a carrier therefor, a presser gage attached to said carrier in fixed relation to said knife, a feed dog, a carrier therefor in fixed lateral relation to the knife carrier, means for reciprocating said carriers simultaneously back and forth, and means for imparting an independent up and down movement to the feed dog carrier. 110
18. A channeling machine comprising channeling knives, presser gages, and feed dogs, one of said feed dogs having a toe or extension extended between the presser gages to ensure the feeding off of the work at the completion of the cutting operation. 115
19. In a channeling machine, a work support comprising a rotary table having a substantially flat upper surface and a downwardly converging conical side wall, terminating in a depending stem provided with a circumferential flange, in combination with a bearing for said stem and a thrust bearing supporting said flange. 120
20. A channeling machine comprising a main frame, a member movable on said frame, work channeling and feeding mecha- 125
- 130

- nisms mounted on said member, a sliding carriage supported on said frame beneath said channeling mechanism, a rotary work table journaled in said carriage, means for moving said carriage in lines transverse to the direction of feed of the work, a chamfering knife carried by said member, and connections between said knife and said carriage to render said knife adjustable simultaneously with the movement of said carriage.
21. A channeling machine comprising a channeling knife, a slide for supporting said channeling knife, means for reciprocating said slide, a chamfer knife carried by said slide to move therewith, and means for adjusting said chamfer knife transversely of the movement of said slide.
22. A channeling machine comprising a channeling knife, a feed dog, a slide by which said channeling knife and feed dog are supported, means for reciprocating said slide to channel and impart feed movements to the work, a chamfer knife carried by said slide to chamfer the edge of the work by the reciprocation of said slide, and means to adjust said chamfer knife transverse to the line of feed.
23. A channeling machine comprising a channeling knife, a feed dog, a slide by which said channeling knife and said feed dog are supported, means for reciprocating said slide, and a chamfering knife supported and reciprocated by said slide.
24. A channeling machine comprising a channeling knife, a feed dog, a slide by which said channeling knife and said feed dog are supported, means for reciprocating said slide, a chamfering knife supported and reciprocated by said slide, a work table bodily movable transversely of the path of movement of said knives, and connections between said table and said chamfering knife to move said knife simultaneously with said table.
25. A channeling machine comprising a channeling knife, a carriage therefor, means for vibrating said carriage, a slide mounted on said carriage to move in lines transverse to the path of movement thereof, and a chamfering knife mounted on said slide.
26. A channeling machine comprising a channeling knife, a carriage therefor, means for vibrating said carriage, a slide mounted on said carriage to move in lines transverse to the path of movement thereof, a chamfering knife mounted on said slide, a work-supporting carriage, movable longitudinally of said slide, and an operative connection between said slide and said work carriage.
27. A channeling machine comprising a pair of channeling knives, a pair of slides on which said knives are respectively supported, feed dogs and appropriate carriers therefor carried by said slides, a shaft, connec-
- tions between said shaft and said slides for reciprocating said slides simultaneously in opposite directions, and connections between said shaft and said carriers for simultaneously reciprocating said feed dogs in opposite directions.
28. A channeling machine comprising a pair of knives, a pair of feeding devices, a pair of slides, each slide carrying a knife and a feeding device, a pair of oppositely disposed eccentrics on said shaft, connections between said eccentrics and said slides by which said slides are reciprocated simultaneously in opposite directions, and a pair of eccentrics on said shaft arranged to reciprocate said feeding devices simultaneously in opposite directions transversely of the paths of movement of said slides.
29. In a channeling machine, a main frame, mechanisms on said frame for feeding and for channeling the work, a guideway on said main frame, a carriage movable in said guideway, a work table journaled in said carriage, a manually-controlled lever, operative connections between said lever and said carriage, and interlocking mechanism for securing said lever at any one of different predetermined positions.
30. In a channeling machine, a channeling knife, a reciprocatory carriage on which said knife is supported, a two-armed lever, a shaft, an operative connection between said shaft and one arm of said lever for oscillating said lever, the other arm of said lever having a longitudinal slot, a link pivoted to said carriage at one end and having a stud at its other end located in said slot and movable toward the axis of oscillation of said lever, and manually-controlled means for adjusting said link to locate said stud in said slot at different distances from said axis to vary the extent of the reciprocation imparted to said carriage.
31. A channeling machine comprising a pair of reciprocatory slides, a channeling knife and a feeding device mounted on each slide, mechanisms for reciprocating said slides simultaneously in opposite directions to cause said knives and feeding devices to cut and to feed the work in alternation, and means for manually controlling the extent of reciprocation of one of said slides.
32. In a channeling machine, a work support, a reciprocatory slide, mechanism for reciprocating said slide, a channeling knife, a yielding carrier therefor supported on said slide, a feeding device supported on said slide, and movable therewith, means for moving said feeding device toward and from the work support, and manually-controlled means for moving the said knife away from said work support.
33. A channeling machine comprising two sets of the following instrumentalities, viz., a channeling knife, a presser gage and a

feed dog arranged in alinement, said sets being arranged side by side; an independent carriage for each of said sets; and mechanism for moving said carriages back and forth simultaneously but in opposite directions, whereby, when the feed dog of one set is moving in one direction to feed the work, the knife of the other set is moving in the opposite direction to channel the work.

34. A channeling machine comprising two sets of the following instrumentalities, viz, a channeling knife, a presser gage and a feed dog arranged in alinement, said sets being arranged side by side; an independent carriage for each of said sets; mechanism for moving said carriages back and forth simultaneously but in opposite directions, whereby, when the feed dog of one set is moving in one direction to feed the work, the knife of the other set is moving in the opposite direction to channel the work; a chamfering knife; and means by which said chamfering knife is reciprocated by one of said carriages.

35. A channeling machine comprising two sets of the following instrumentalities, viz, a channeling knife, a presser gage and a feed dog arranged in alinement, said sets being arranged side by side; an independent carriage for each of said sets; mechanism for moving said carriages back and forth simultaneously but in opposite directions, whereby, when the feed dog of one set is moving in one direction to feed the work, the knife of the other set is moving in the opposite direction to channel the work; a chamfering knife; means by which said chamfering knife is reciprocated by one of said carriages; a work table arranged to move bodily transversely of the direction of feed of the work; and means by which the chamfering knife is moved in unison with said table relatively to the last-mentioned slide.

36. In a channeling machine, means for feeding the work, a pair of upright knife carriers each having a laterally-extending head at its lower end, an inner channeling knife attached to one of said heads, an outer knife attached to the other head, and means for simultaneously reciprocating said carriers in lines parallel with the direction of feed of the work but in opposite directions.

37. In a channeling machine, means for feeding the work, a pair of upright knife carriers each having a laterally-extending head at its lower end, an inner channeling knife attached to one of said heads, an outer knife attached to the other head, means for simultaneously reciprocating said carriers in lines parallel with the direction of feed of the work but in opposite directions, and manually-controlled means for moving said

knife carriers longitudinally or upwardly to lift them from the work.

38. In a channeling machine, a reciprocating carriage, a shaft, operative connections between said shaft and said carriage, a feed dog, a reciprocating carrier therefor slidably mounted in said carriage, and comprising a yielding member on which said feed dog is secured, a member reciprocated by said shaft, a spring interposed between said members and tending to separate them, and a sliding member connecting said members to limit their separation.

39. In a machine of the class described, a knife reciprocating in the line of feed of the work and arranged to cut upon its backward stroke, and means for feeding the work against the knife while the knife is moving backwardly and for feeding the work with the knife during the forward stroke of the knife.

40. In a machine of the class described, a knife reciprocating in the line of feed of the work and arranged to cut upon its backward stroke, and alternately operated feed devices for advancing the work during both the backward and forward strokes of the knife.

41. In a machine of the class described, a knife reciprocating in the line of feed of the work and arranged to cut upon its backward stroke, a reciprocating feed dog for advancing the work during the backward stroke of the knife, and a second reciprocating feed dog for advancing the work during the forward stroke of the knife.

42. In a machine of the class described, a knife reciprocating in the line of feed of the work and arranged to cut upon its backward stroke, and means for feeding the work through a distance substantially equal to the length of knife stroke while the knife is moving backwardly and for feeding the work a like distance while the knife is moving forwardly.

43. In a machine of the class described, feed mechanism intermittently operative to advance the work, and means movable opposite to the direction of feed to cut the work while the work is being advanced by said mechanism and in the direction of feed to impart an auxiliary feed movement to the work while said feed mechanism is inoperative.

44. In a machine of the class described, feed mechanism intermittently operative to advance the work, means movable opposite to the direction of feed to cut the work while the work is being advanced by said feed mechanism, and an auxiliary feed device for advancing the work while said feed mechanism is inoperative.

45. In a machine of the class described, feed mechanism intermittently effective to

- advance the work, a reciprocating knife moving opposite to the direction of feed to cut the work while the work is being advanced by said feed mechanism, and means effective during the non-cutting stroke of the knife for advancing the work with the knife. 5
46. In a machine of the class described, a work support, a reciprocating feed member effective upon its forward stroke to feed the work, a reciprocating knife effective upon its backward stroke to cut the work, and means for actuating the feed member and knife simultaneously in opposite directions during the cutting stroke of the knife. 10
47. In a machine of the class described, a reciprocating feed device operative upon its forward stroke to advance the work, a knife reciprocating in the line of feed and operating to cut the work on its backward stroke, and means for imparting a backward stroke to the knife during the forward stroke of the feeding device and a forward stroke to the knife during the backward stroke of the feeding device. 15
48. In a machine of the class described, a reciprocating feed device operative upon its forward stroke to advance the work, a knife reciprocating in the line of feed and operating to cut the work on its backward stroke, and means for imparting a backward stroke only to the knife during the forward stroke of the feeding device. 20
49. In a machine of the class described, a reciprocating feed device operative upon its forward stroke to advance the work, a knife reciprocating in the line of feed and operating to cut the work on its backward stroke, and means for imparting a backward stroke to the knife continuing during the forward stroke of the feeding device. 25
50. In a machine of the class described, a knife reciprocating in the line of feed of the work, means for feeding the work against the cutting edge of the knife throughout the cutting stroke of the knife and for feeding the work in unison with the knife throughout the non-cutting stroke of the knife. 30
51. In a machine of the class described, cutting means, work-feeding means, means for moving the cutting means opposite to the direction of feed to cut the work while the work is being fed, means for operating the feeding means to feed the work while the cutting means is operating to cut the work, and other means to impart an additional feed movement to the work while the cutting means is ineffective to cut the work. 35
52. In a machine of the class described, cutting means, work-feeding means, and means for operating them to cause the cutting means to move opposite to the direction of feed to cut the work while the feeding means is feeding the work and to return to starting position while said feeding means is ineffective to feed the work, in combination with means for imparting an additional feed movement to the work while the cutting means is returning to starting position. 40
53. In a machine of the class described, feeding means intermittently operative to feed the work, cutting means movable opposite to the direction of feed to cut the work while said feeding means is operative and movable to its starting position while said feeding means is inoperative, and means for imparting an additional feed movement to the work while said cutting means is returning to starting position. 45
54. In a machine of the class described, work feeding means, cutting means moving opposite to the direction of feed to cut the work while the work is being fed, means for operating the feeding means to feed the work while said cutting means is operating to cut the work, and means for further feeding and cutting the work while said feeding means and said cutting means are ineffective. 50
55. In a machine of the class described, work feeding means, cutting means moving opposite to the direction of feed to cut the work while the work is being fed, means for operating the feeding means to feed the work while said cutting means is operating to cut the work, other means to impart an additional feed movement to the work while said cutting means is ineffective to cut the work, and other cutting means for cutting the work during said additional feed movement. 55
56. In a machine of the class described, a reciprocating feed device operative upon its forward stroke to advance the work, a reciprocating knife moving opposite to the direction of feed to cut the work while the work is being advanced by said feed device, and auxiliary feeding means for advancing the work during the return stroke of said feed device. 60
57. In a machine of the class described, feed mechanism intermittently effective to advance the work, a reciprocating knife moving opposite to the direction of feed to cut the work while the work is being advanced by said feed mechanism, and reciprocating means movable with said knife during the non-cutting stroke of the latter for imparting an auxiliary feed movement to the work. 65
58. In a machine of the class described, two reciprocating feed devices, means for rendering said devices alternately and successively effective to advance the work, and a cutter moving in timed relation with the feed devices to cut the work while one feed device is advancing the work and to be retracted with the work while the work is being advanced by the other feed device. 70
59. In a machine of the class described, a work support, two reciprocating feed devices 130

- operating upon their forward strokes to feed the work, mechanism for actuating said feed devices simultaneously in opposite directions through strokes of equal length, and a knife 5 reciprocating in unison with one of said feed devices and operative upon the backward stroke of the latter for cutting the work.
60. In a machine of the class described, a reciprocating feed member and a reciprocating knife movable simultaneously in opposite directions through strokes of equal length for feeding and cutting the work, and auxiliary means operative during the idle stroke of said feed member and concurrent non-cutting stroke of said knife for feeding the work through the same distance as said feed member.
61. In a machine of the class described, a work support, a reciprocating feed member 20 effective upon its forward stroke to feed the work, a reciprocating knife effective upon its backward stroke to cut the work, means for actuating the feed member and knife simultaneously in opposite directions, auxiliary feeding means for advancing the work while said feed member is inoperative, and a presser gage associated with said knife to determine the depth of cut.
62. In a machine of the class described, a main feed mechanism intermittently operative to advance the work, a reciprocating knife moving opposite to the direction of feed to cut the work while the work is being advanced by said feed mechanism, and 35 a four-motion feed dog arranged to impart an auxiliary feed movement to the work while said main feed mechanism is inoperative and said knife is moving in the direction of feed.
63. In a machine of the class described, reciprocating inner and outer knives movable simultaneously in opposite directions in the line of feed of the work and arranged to 40 cut upon their backward strokes, a work-engaging four-motion feed dog movable forwardly with the inner knife for feeding the work against the outer knife while said outer knife is moving backwardly, and a second work-engaging four-motion feed dog 45 movable forwardly with the outer knife for feeding the work against the inner knife while the latter is moving backwardly.
64. In a machine of the class described, two reciprocating slides, mechanism for actuating said slides simultaneously in opposite directions, a feed device on one slide effective during the forward movement of 50 said slide to feed the work, and means on the other slide effective on the backward stroke of the latter to cut the work.
65. In a machine of the class described, two reciprocating slides, mechanism for actuating said slides simultaneously in opposite directions, a feed device on one slide effective during the forward movement of 55 said slide to feed the work, and means on the other slide effective on the backward stroke of the latter to cut the work.
- said slide to feed the work, and means on the other slide effective on the backward stroke of the latter to cut the work and on the forward stroke thereof to feed the work.
66. In a machine of the class described, 70 two reciprocating slides, mechanism for actuating said slides simultaneously in opposite directions, a feed device on one slide effective during the forward movement of said slide to feed the work, and a knife on the other slide for cutting the work when said slide is moved rearwardly.
67. In a machine of the class described, 75 two reciprocating slides, mechanism for actuating said slides simultaneously in opposite directions, a feed device on one slide effective during the forward movement of said slide to feed the work, a knife on the other slide for cutting the work when said slide is moved rearwardly, and means on the knife slide for imparting an auxiliary feed movement to the work while the knife is moving forwardly.
68. In a machine of the class described, 80 two reciprocating slides, mechanism for actuating said slides simultaneously in opposite directions, a knife on each slide arranged to cut the work upon the backward stroke of the slide, and a feed dog carried by each slide effective to advance the work 85 upon the forward movement of the slide.
69. In a machine of the class described, 90 two reciprocating carriers, a knife on one of said carriers, a feeding device on each of said carriers, means for moving said carriers simultaneously in opposite directions to cause said knife and said device to cut and to feed in alternation, and means for controlling the extent of reciprocation of the knife-carrier.
70. In a machine of the class described, 95 two reciprocating slides, a knife carried by one of said slides for cutting an inner channel in a sole, a knife carried by the other of said slides for cutting an outer channel 100 in a sole, means carried by each of said slides for feeding the sole, means for moving said slides simultaneously in opposite directions to cause said knives and said feeding means to act in alternation to cut and feed the sole, and means for controlling the extent of reciprocation of the slide carrying the knife for cutting the inner channel.
71. In a machine of the class described, 105 two knives, means for simultaneously reciprocating the knives in opposite directions, and means having a movement of the same character as that of the knives for feeding the work while one of the knives is moving in a direction opposite to the direction of feed to cut the work.
72. In a machine of the class described, 110 two knives, means for reciprocating said knives simultaneously in opposite directions to cut in alternation, and means associated 115
- 120
- 125
- 130

with each knife and immovable relatively to the work while the other knife is cutting the work for feeding the work against the cutting stroke of the other knife.

- 5 73. In a machine of the class described, two reciprocating slides, a knife on one of said slides for cutting an outer channel in a sole, a knife on the other of said slides for cutting an inner channel in a sole, a
  - 10 feed dog on each of said slides, means for moving the slides simultaneously in opposite directions to cause said knives and feed dogs to cut and feed the work in alternation, and means for controlling the length of stroke of
  - 15 the slide carrying the knife for cutting the inner channel.
74. In a machine of the class described, a reciprocating knife for cutting an outer channel in a sole, a reciprocating feed device
- 20 for feeding the sole against the knife, means for moving the knife and the feed device

simultaneously in opposite directions to feed and cut the work, auxiliary means for advancing the work between the cutting strokes of the knife, and means for varying the 25 length of stroke of said feed device while the machine is running.

75. In a machine of the class described, a reciprocating knife for cutting an inner channel in a sole, a reciprocating feed device 30 for feeding the sole against the knife, means for moving the knife and the feed device simultaneously in opposite directions to feed and cut the work, auxiliary means for advancing the work between the cutting strokes 35 of the knife, and means for varying the length of stroke of the knife while the machine is running.

In testimony whereof I have affixed my signature.

HARRIE A. BALLARD.
